(57) **CLAIM**

The ornamental design for a charging brick, as shown and described.

DESCRIPTION

FIG. 1 shows a perspective view showing front, bottom, and right sides of a charging brick showing our new design;

FIG. 2 shows a front plan view thereof;

FIG. 3 shows a back plan view thereof;

FIG. 4 shows a right side elevation view, the left side elevation view being a mirror image thereof;

FIG. 5 shows a bottom elevation view thereof; and,

FIG. 6 shows a top elevation view thereof.

The broken lines illustrate structure or features which form no part of the claimed design.

1 Claim, 5 Drawing Sheets
